Inventor

Thomas J. Manning,

By his Attorney
John C. Dewey.

UNITED STATES PATENT OFFICE.

THOMAS J. MANNING, OF GRAFTON, MASSACHUSETTS.

SLATE-PENCIL SHARPENER.

SPECIFICATION forming part of Letters Patent No. 378,329, dated February 21, 1888.

Application filed November 21, 1887. Serial No. 255,686. (No model.)

To all whom it may concern:

Be it known that I, THOMAS J. MANNING, a citizen of the United States, residing at Grafton, in the county of Worcester and State of Massachusetts, have invented certain new and useful Improvements in Slate-Pencil Sharpeners; and I do hereby declare that the following is a full, clear, and exact description thereof, which, in connection with the drawings making a part of this specification, will enable others skilled in the art to which my invention belongs to make and use the same.

My invention relates to slate-pencil sharpeners; and the object of my invention is to produce a very cheap and serviceable sharpener which shall have sharpening-surfaces on all sides thereof.

My invention consists in certain novel features of construction of a slate-pencil sharpener, as will be hereinafter fully described.

Referring to the drawings, Figure 1 is a perspective view of my improved sharpener, and Fig. 2 is an end view thereof.

In the accompanying drawings, 1 is my improved sharpener, consisting of a block of wood, 2, made in one piece, of X shape in cross-section, and having four V-shaped grooves, 3, extending longitudinally therein, one on each side, from end to end, and parallel to each other. The projecting parts 4, extending out in opposite directions from the central part of the block 2, are preferably made of angular shape at their ends, so that there will be flat surfaces 5, upon which the block 2 may squarely and firmly rest. (See Figs. 1 and 2.)

The V-shaped grooves 3 in the block 2 are coated or covered with a sharpening or abrading material, preferably fine sand or emery-powder, 6, which I have shown in the drawings as covering and coating all of the block except the ends thereof.

The emery-powder, 6, is made to adhere to

the block 2 by means of thin glue or other adhesive material, which is first spread over all 45 of the surface of the block 2, and more especially in the V-shaped grooves 3, in which the slate-pencil to be sharpened is moved back and forth.

If preferred, the flat surfaces 5 on the projecting parts 4 may be left free of the emery-powder or other abrading material, in order that the sharpener may not scratch or mar whatever it is placed upon.

The great advantage of my improved slate-pencil sharpener is that I provide four separate sharpening-surfaces, so that when one wears out the sharpener is turned a quarter of a revolution and a second surface is presented, and so on; and, further, my improved sharpener can be made very cheaply in the following manner: A long square strip of wood is run through a molding-machine, which cuts it into the shape shown in cross-section. Said strip is then cut up into the lengths desired for each 65 sharpener and dipped into glue or other adhesive material, and then emery-powder or other abrading material is applied thereto, and the sharpener is finished and ready for immediate use.

Having thus described my invention, what I claim as new, and desire to secure by Letters Patent, is—

As a new article of manufacture, a slate-pencil sharpener consisting of a block, 2, of X 75 shape in cross-section, and having four longitudinal V-shaped grooves therein coated with abrading material, and projecting parts 4, extending out in opposite directions from the central part of said block, and provided with 80 angular ends, for the purpose stated, substantially as shown and described.

THOMAS J. MANNING.
